UNITED STATES PATENT OFFICE.

EDWARD LEE AND JOHN STANFELD PICKFORD, OF LONDON, ENGLAND,
ASSIGNORS TO THE NATIONAL BAKERY COMPANY, LIMITED, OF SAME
PLACE.

SHOW-CASE, &c.

SPECIFICATION forming part of Letters Patent No. 663,505, dated December 11, 1900.

Application filed August 24, 1897. Serial No. 649,380. (No model.)

To all whom it may concern:

Be it known that we, EDWARD LEE and JOHN STANFELD PICKFORD, subjects of the Queen of England, residing at London, England, have invented certain new and useful Improvements in or Relating to Show-Cases and the Like, of which the following is a specification.

This invention relates to improvements in connection with the construction of showcases or boxes and the like, its object being to produce a show-case or frame having entirely-detachable show-faces, so that it is not necessary to form a portion of the box or frame with a permanent glazed front, as is now commonly done.

The invention is particularly applicable to tins for biscuits, confectionery, and the like and may be conveniently described in connection with the same.

In the accompanying drawings, Figure 1 is a view, partly in plan and partly in horizontal section, of a form of biscuit tin or frame constructed according to our invention with the two show-faces in position therein; and Fig. 2 is a back elevation of the same device as that shown in Fig. 1, with the show-faces removed. Fig. 3 is a perspective view showing a pair of show-faces hinged together in the manner hereinafter described. Fig. 4 is a perspective view of the biscuit-tin shown in Figs. 1, 2, and 3. Fig. 5 is a vertical section through one of the show-faces.

Like letters indicate like parts throughout the drawings.

In the device shown in the accompanying drawings the two show-faces B B' are fitted into a triangular frame or box A⁷, the top of which is preferably permanently secured in its closed position, and each of the show-faces is beveled at both of its vertical edges, as shown at b⁶ in Fig. 1. The frame A⁷, which is somewhat deeper from top to bottom than are the show-faces B B', is provided with brackets or projections a³ for retaining the show-faces in position and with a sliding door or equivalent A⁸, (which in Fig. 2 is shown partly raised), for admitting of the show-face

B being inserted after the show-face B' has been placed in position, and a closed part A¹⁰. 50 The parts A⁸ A¹⁰ and the mutual engagement of the faces B B' retain both of the show-faces within the frame A⁷.

Each of the show-faces B B' comprises a frame b, having its front b' of glass or other 55 transparent material and its lid or back b² removable, so that access may be had to the space b³, Fig. 5., between the said front and back, for placing biscuits or other goods C in this space, as shown in Figs. 4 and 5. For 60 ornamental purposes a gilt or other mount D may be fitted in the show-faces at the back of the glazed or other transparent front b', and, if desired, this mount as well as the said front, may be readily removable from the show- 65 face.

In fitting the two separated show-faces B B' in the frame A⁷ first the show-face B' is inserted through the open back of the frame A⁷ and moved into its proper position behind the opening A⁴ and then while the door or equivalent A⁸ is sufficiently raised or entirely withdrawn the show-face B is inserted through the opening A⁹ and pressed "home," after which the door A⁸ is lowered or closed, so as 75 to retain the show-face B, and consequently the show-face B', in the proper position within the frame A⁷.

Where two show-faces are employed with their vertical edges adjacent, those edges may 80 be hinged together as at b⁷, Fig. 3, so as to connect the two faces, which may then be very conveniently folded face to face for convenience of storage and transport and protection of their glass panes. When the two faces are 85 hinged together, they may be both most conveniently inserted in the frame A⁷ through the opening A⁹.

Without limiting ourselves to the precise construction and arrangement of the parts 90 shown and described, what we claim is—

1. A show-case comprising a triangular frame, with two internal removable show-faces and with a sliding end A⁸ and blocked end A¹⁰, substantially as and for the purpose 95 described.

• 2. A show - case comprising a triangular frame, with two internal removable show-faces hinged together at their adjacent vertical edges, and with a sliding end A⁸ and 5 blocked end A¹⁰, substantially as and for the purpose set forth.

In witness whereof we have hereto set our

hands in the presence of the two subscribing witnesses.

EDWARD LEE.

JOHN STANSFELD PICKFORD.
